ATTORNEY

UNITED STATES PATENT OFFICE.

LARS L. FURAN, OF THIEF RIVER FALLS, MINNESOTA.

RAZOR-BLADE-STROPPING DEVICE.

1,253,226.

Specification of Letters Patent. Patented Jan. 15, 1918.

Application filed June 14, 1917. Serial No. 174,813.

To all whom it may concern:

Be it known that I, LARS L. FURAN, a citizen of the United States, residing at Thief River Falls, in the county of Pennington and State of Minnesota, have invented certain new and useful Improvements in Razor-Blade-Stropping Devices, of which the following is a specification.

This invention relates to improvements in 10 razor-blade stropping devices and has for its object to provide traveling straps for stropping the blade.

Another object of the invention is to provide cylinders for rotating the straps and 15 means whereby the straps travel in a straight line for stropping razor blades.

A still further object of the invention is to provide a pair of traveling straps for stropping the opposite sides of a razor blade 20 in combination with means for alternately shifting the blade from one strap to another.

With the above and other objects in view 25 I have invented the device illustrated in the accompanying drawings in which;

Figure 1 is a top plan view of my invention, and,

Fig. 2 is a section taken on the line A—A of Fig. 1.

Like reference characters indicate like parts throughout the following specification and in the several views in the drawings in which 1 is a casing having alined bearing plates 2 and 3 for supporting each of the 30 shafts 4 and 5, upon which cylinders 6 and 7 are fixed. Mounted on the bottoms of the cylinders are gears 8 and 8' which mesh with one another, whereby the cylinders operate in unison. Rotatably mounted on the 35 cylinders are endless leather stropping belts 9 and 10 which are longer than the circumference of the cylinders and which are held taut by rollers 11 and 12 supported upon brackets 13 and 13' and similar brackets 14. These brackets are each provided with screw 40 ends 15 operating through the wall 16 of the casing and controlled by nuts 17 and 18 whereby they may be adjusted to the straps and locked in position. The rollers 11 and 45 12 are in alinement with the inner peripheral portions 17' and 18' of the cylinders whereby said belts travel in a straight line 50 for a desired distance between the cylinders for the purpose of grinding the opposite sides 19 and 20 of the razor blade 21 which

is held between said straight portions 22 and 23 of said belts, in the blade supporting bracket 24 which is mounted upon arms 25 and 26 secured to the wall 27 of the casing 1 in the same manner as said brackets 13 and 14. Arm 25 has a bearing sleeve 25' in which the bracket 32 may be rocked or oscillated. Said arms 25 and 26 may be adjusted relative to one another in order to hold said razor blade 21 in any desired angular stropping position.

The blade supporting bracket 24 is provided with resilient walls 28 and 29 between which the razor blade 21 is securely clamped whereby said blade is held in proper position for stropping. The resilient clamp 30 on the upper end of the member 24 holds the handle 31 of the razor, on the bar 32 of the bracket. The blade supporting bracket 24 is perforated to accommodate a rod 33 passing transversely therethrough, and this rod is attached to the opposite sides of a bow-shaped yoke 35 adapted to shift or oscillate, laterally and freely, the rod 33 passing through the opening in the bracket 24, and oscillating the bracket, as will be understood. The member 35 is held under tension by means of a spring 36, one end of which is secured to the wall 27.

Pivotedly mounted upon the upper ends 37 and 38 of the cylinders 6 and 7 are arms 39 and 40, which are controlled in their movements by staples 41 and 42 and which are held in normal position by means of springs 43 and 44. These arms on every second rotation of the cylinders engage first the one side 45 and then the other side 46 of the shifting member 35 and cause the same to shift the razor support 24 whereby the blade will first engage one belt 22 and 55 then the other belt 23. On the shaft 5 is a pinion 47, operated by a pinion 48 on the crank shaft 49 which is operated by the crank handle 50, the rotation of said handle causing the rotation of the cylinder 7, the gear 8 of which operates the gear 8' which is fixed to and rotates the cylinder 6. By means of the action of the arms 39 and 40 the razor blade is alternately shifted from one of the stropping belts to the other in 60 105 suitably successive movements, whereby the blade may be properly sharpened.

It will of course be understood that the razor supporting device 24 may be adapted to any make of razor or safety razor blade.

110

Having thus described my invention, that which I claim as new and desire to secure by Letters Patent is:

1. A blade sharpening device comprising a pair of spaced, revolving, cylinders, an endless stropping belt on each cylinder, and a spaced guide roller for each belt, an oscillatable blade supporting device located between the cylinders and means on each cylinder to oscillate said supporting device toward the other cylinder.
  2. A blade sharpening device comprising a pair of spaced, revolving cylinders, an endless stropping belt on each cylinder, and a spaced guide roller for each belt, an oscillatable blade supporting device located between the cylinders, and a resiliently supported arm on each cylinder adapted to oscillate said supporting device toward the other cylinder.
  3. A blade sharpening device comprising a pair of spaced, revolving cylinders, an endless stropping belt on each cylinder, and a spaced guide roller for each belt, an oscillatable blade support, an oscillatable yoke operatively connected therewith, and a resiliently supported arm on each cylinder adapted to oscillate said yoke toward the other cylinder.
4. The combination with a pair of parallel traveling stropping belts, of an oscillatable, perforated blade support, an oscillatable yoke having a guide rod passing through said support, and means for oscillating said yoke.
5. The combination with a pair of revolving cylinders, an endless stropping belt on each cylinder, and a spaced guide roller for each belt, of an oscillatable, perforated bracket having resilient blade clasping walls, a yoke having a transverse rod passed loosely through the perforated bracket, a retaining spring attached to the yoke, and a resilient arm on each cylinder adapted to contact with the yoke to oscillate the yoke toward the other cylinder.

In testimony whereof I affix my signature in the presence of two witnesses.

LARS L. FURAN.
